UNITED STATES PATENT OFFICE.

WILLIARD HORTMAN, OF BERWICK, PENNSYLVANIA.

SIGNAL.

Application filed July 23, 1924. Serial No. 727,760.

This invention relates to a signal for motor vehicles and the like, the general object of the invention being to provide a signal member made in the form of a hand and a casing with means for normally holding the hand within the casing so that it cannot be seen and with means for causing the hand to project from the casing when the vehicle is to make a turn or is to be stopped.

Another object of the invention is to provide means for illuminating the hand when the same is in operative position.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a view showing the invention in use with the hand in operative position.

Figure 2 is a side view of Figure 1 with parts broken away.

Figure 3 is a section on line 3—3 of Figure 1.

Figure 4 is a sectional view through the casing of the device showing the interior parts thereof.

Figure 5 is a section on line 5—5 of Figure 4.

Figure 6 is a sectional detail view showing the switch for controlling the circuit to the lamp.

Figure 7 is a view of one section of the hand.

Figure 8 is a view of the other section.

In these views, 1 indicates a casing which has one side open and which is adapted to be fastened to the windshield frame of a vehicle by the clamp 2. A sectional signal A is pivotally mounted in the casing in such a manner that when it is in inoperative position it lies within the casing and cannot be seen and when it is in operative position it extends through the open side of the casing so that it can be seen by pedestrians and drivers of other cars. This signal is preferably made in the form of a hand and is composed of the two sections 3 and 4.

The section 4 is pivoted to one wall of the casing by means of the pin 5 and the section 3 is movably connected with the section 4 by means of the pin 6 which passes through a hole 7 in section 3 and through an arc-shaped slot 8 in section 4 and by means of a pin 9 on section 3 engaging an arc-shaped slot 10 in section 4. A lever 11 is pivoted at 12 to a part of the casing and the front end of this lever is provided with a slot 13 through which the pin 6 passes. A spring 14 is suitably supported in the casing, preferably by means of the plate 15, and has its outer end connected with the pin 6. This spring tends to hold the parts with the signal A in operative or projected position, as shown in full lines in Figure 4. A cable 16 is connected with the pin 6 and passes through a conduit 17 fastened to the vehicle and the other end of the cable is fastened to a lever 21 which is pivoted to a part of the vehicle and is engaged by a spring 22 which is fastened to either the clutch pedal or the brake pedal B. This spring is so arranged that it may be depressed by the foot without depressing the pedal though it will be moved away from the lever when the pedal is depressed. These parts are so arranged that when the pedal is in its normal position the cable 16 is stretched so as to pull the lever 11 and the spring downwardly and thus move the two sections of the signal into the casing, as shown in dotted lines in Figure 4. As soon as the pedal B is pushed inwardly to check or stop the car the cable will be slackened and then the spring will throw the signal member outwardly, as shown in full lines in Figure 4, thus indicating that the car is to make a turn or is to stop. The same action will occur if the spring 22 is depressed by the foot without depressing the pedal B. As will be seen the section 3 has limited movement on section 4 so that at the beginning of the inward movement the section 3 will move upwardly until it overlies the section 4 and then the pins engaging the ends of the slots will cause the section 4 to move upwardly with the section 3 until both sections lie within the casing, as shown in dotted lines in Figure 4. On the outward movement of the parts the section 4 will come to rest upon the bottom of the casing before the section 3 ceases its movement and when both sections come to rest they will

occupy the position shown in Figure 4 with the section 4 slightly above the section 3, thus making the signal in the form of a hand with the fingers and thumb extended.

5 A lamp 18 is placed in the casing for illuminating the hand and this lamp may be electrically connected with the battery of the car. It is provided with a switch 19 which is engaged by the pointed end 20 of 10 the arm or lever 11 when the same is in raised position so as to complete the circuit to the lamp when the signal arm is in operative position so that the rays of light from the lamp will illuminate the hand and 15 thus permit the signal to be visible at night. When the arm is in its downward position it will release the switch so that current will not flow to the lamp.

From the foregoing it will be seen that I 20 have provided a simple and a practical device for indicating the intentions of a driver of a vehicle when he is about to make a turn or is to make a stop. The device is wholly automatic and does not require any action on 25 the part of the driver as the signal will move into active position as soon as the spring 22, or the brake pedal or the clutch pedal is depressed. The device can be used on closed cars as well as open cars.

30 I also place a mirror 24 on the rear of the

casing so as to permit the driver to have a view of the road in the rear of the vehicle.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A device of the character described including a casing, a sectional signal member in the casing, a pin for pivotally connecting the two sections, slot and pin connections between the two sections for limiting the relative movement of said sections with respect to each other, an actuating lever pivoted within the casing and having one end slotted, a pin having pivotal connection with the sections of the signal and movable in said slot, a spring member connected to one wall of the casing and having its outer end attached to the last mentioned pin whereby to normally project said signal member from the casing and manually operated means for actuating said signal member.

In testimony whereof I affix my signature.

WILLIARD HORTMAN.
